UNITED STATES PATENT OFFICE.

EDMUND C. MORGAN, OF NEW YORK, N. Y.; OLIVE EUGENIE MORGAN EXECUTRIX OF
SAID EDMUND C. MORGAN, DECEASED.

MINING MACHINE.

Application filed March 20, 1916, Serial No. 85,243. Renewed January 22, 1923.

To all whom it may concern:

Be it known that I, EDMUND C. MORGAN, a citizen of the United States, residing at New York, in the county of New York and State of New York, have invented certain new and useful Improvements in Mining Machines, of which the following is a specification.

This invention relates to machines for mining coal and other similar substances, and has for its object the provision of a device of the character named which shall be of improved construction and more efficient in its operation than machines of this character heretofore known. The invention is exemplified in the combination and the arrangement of parts shown in the accompanying drawings and described in the following specification and it is more particularly pointed out in the appended claims.

In the drawings:

Fig. 1 is a diagrammatic plan view of the machine in operative position in a mine chamber.

Fig. 2 is a vertical section through a mine chamber representing diagrammatically the machine in operative position.

Fig. 3 is a side elevation of the machine as it appears during the process of making a cut.

Fig. 4 is a top plan view of the complete machine and a portion of a conveyor used in connection therewith.

Fig. 5 is a fragmentary horizontal sectional view on the level of the line 5-5 of Fig. 7 but showing parts of the machine not illustrated in the latter view.

Fig. 5^a is an enlarged sectional elevation of the interior construction of a planetary gear and brake mechanism shown at 70' in Fig. 5.

Fig. 5^b is a sectional elevation of a portion of Fig. 5 to show the planetary gear connections between the driving mechanism and the worm gearing of the spaced apart horizontal kerf cutters.

Fig. 5^c is a fragmentary sectional elevation to show the connections between the driving mechanism and the chain core cutting mechanism.

Fig. 6 is a vertical sectional view on line 6-6 of Fig. 5.

Fig. 7 is a vertical sectional view on line 7-7 of Fig. 5.

Fig. 8 is a section on line 8-8 of Fig. 6.

Fig. 8^a is a detail of a cam action used for driving a portion of the machine.

Fig. 9 is a fragmentary sectional view of a material moving device forming part of the invention.

Fig. 10 is a fragmentary sectional view on line 10-10 of Fig. 6.

Fig. 11 is a detail of a part used in connection with the screw support for the machine.

Fig. 12 is a horizontal sectional view of a modified form of the invention.

Fig. 13 is an elevational view of the form of the invention shown in Fig. 12, and

Fig. 14 is a detail of a portion of the form of the invention shown in Figs. 12 and 13.

Referring first to Figs. 1 to 11 inclusive, the numeral 20 designates a supporting frame member provided with a base 21 arranged to rest upon the floor of the mine chamber, as shown in Figs. 2 and 3. The frame member 20 is also provided with a pair of upright standards 22 provided with pivot pins 23 at their upper ends. A vertically swinging frame 24 is carried by the pivot pins 23 and comprises a base plate 25 and an upstanding guard wall 26. The uprights 22 are provided at their upper ends with internally threaded sleeves 27 in which anchor bars 28 are adjustably secured. The bars 28 are provided at their upper ends with pointed portions for engaging the roof of the mine chamber and are also provided with hand wheels 29 for adjusting the bars in their respective sleeves to force their pointed ends into contact with the mine roof.

The base plate 25 of the pivoted frame work 24 is provided at its forward end with a circular opening 30, as will be seen from Figs. 5, 6, 7 and 8. Projecting inwardly from the periphery of the opening 30 is a flange 31 forming a circular track or slideway for the circular plate 32 which rests upon the flange 31 and is capable of rotation thereon. A flat ring 33 is secured to the base plate 25 and overlaps the edge of the plate 32 to form a guide for holding the plate 32 in position. Integral with the plate 32 and projecting upwardly therefrom in spaced relation from one another near the front portion of the plate is a pair of uprights 35 and 36. These uprights have supports for holding in place the operating mechanism for the movable parts of

the mining machine. A vertical sleeve 37 is carried by brackets 38 and 39 extending horizontally from the uprights 35 and 36, the sleeve 37 being positioned centrally over an opening 40 in the rotary plate 32. The supports 35 and 36 are also provided with upstanding pedestals (one of which is shown at 42 in Fig. 6), which are provided with bearings 43 and 44 in which is journaled a horizontal shaft 45. Carried by the support 35, as shown in Figs. 4, 5, 6 and 7, is a table or platform 46. The platform 46 has a circular outer periphery arranged to overlie approximately the outer periphery of the rotary plate 32. As shown in Figs. 6 and 7 the table 46 is provided with a laterally extending bracket portion 47 which is provided with a collar 48 having an opening therethrough arranged in alignment with the opening in the sleeve 37. To assist in supporting the collar 48 and the table 46 the bracket 47, as shown in Fig. 7, is provided with an arm which is secured to the upright 35. In fact, the entire framework, including the plate 32, the uprights 35 and 36 and the table 46, constitutes a single integral casting.

The support 21 is provided with a forwardly projecting tongue 50 having slide-ways 51 between which is mounted a block 52 arranged to move backwardly and forwardly between the ways 51. Carried by the block 52 is an upright standard 53 which is held in its supporting block by a pin 54. While the upright 53 is free to oscillate about the pin 54 as a pivot it is prevented from rotation about its axis by this pivot pin. The entire upper portion of the standard 53 is provided with screw-threads 55. The screw-threaded portions 55 of the standard 53 cooperates with the internally threaded portion of a worm nut 56 held in place between the collar 48 and the lower end of the sleeve 37. A plate or washer 57 is positioned between the upper surface of the worm nut 56 and the lower end of the sleeve 37. This washer, as shown in Fig. 11, is held from rotation on the standard 53 by means of keys 58 but is free to slide longitudinally along the standard. The washer 57 carries a projection 59 having an opening 60 therein which is provided with a pin 61 arranged to pass through the opening 60 and enter a corresponding opening 62 in the upper surface of the worm nut 56. By means of this pin 61 it is apparent that the worm nut 56 may be locked against rotation on the standard 53. When the pin 61 is withdrawn from the opening 62, however, the worm nut 56 may be rotated to move the frame-work, including the sleeve 37, the collar 48, the uprights 35 and 36, the table 46 and all of the parts supported by this frame-work upwardly or downwardly along the standard 53.

The mechanism for rotating the worm nut 56 will be best understood by referring to Figs. 5, 5^a, 5^b and 6. A motor 65 is mounted on the platform 46 and is provided with a horizontally extending shaft 66 which carries a worm 67 meshing with a worm wheel 187, shown in Fig. 5^b connected through the planetary gearing to the worm 68. Connected to the worm wheel 187 is a shaft 188 to which is splined the clutch element 69; 75 and when the clutch element 69 is moved to the left by means of a lever 189, rotary motion is transmitted to the inner spur gear 190. The rotation of the spur gear 190 causes the rotation of the gears 191 and 192 in opposite directions, and therefore causes the latter to travel around the internal gear 193 in the same direction while occupying diametrically opposite positions on the ends of the spider 194. This spider 194 is keyed to the sleeve 195 which in turn is connected to the worm 68 so as to rotate the latter whenever said sleeve 195 is rotated. It should be understood, however, that the shaft 188 is not connected to either the worm 68 or the sleeve 195, but is mounted loosely within the latter and is connected only to the worm wheel 187 and to the clutch element 69. The casing 196 is provided with a hub 197 at one side for free rotation on the sleeve 195, and on the other side fits on the projecting hub 198 of the central gear 190. The peripheral surface of the casing 196 constitutes a brake pulley 199, and associated therewith is a brake band 200 which is rigidly connected at one end 201 to the standard 202 which is fixed to the base plate 46. The other end, 203, of the brake band 200 is provided with a screw-threaded opening through which extends the screw-threaded rod 204, so that when the latter is turned by means of the wheel 205, the brake band 200 may be applied to the brake pulley 199 so as to hold the internal gear 193 stationary whenever desired. When the brake band 200 is released, the internal gear 193 will be free to turn when the clutch 69 is thrown in and power is transmitted to the gear 190, and therefore no motion will be transmitted to the worm 68, but when the brake band 200 is applied, the gear 193 will be held stationary, and then when the clutch 69 is thrown in the spider 194 will be rotated and thereby transmit rotary movement to the sleeve 195 and also to the worm 68 to which the sleeve 195 is connected for rotation. By fully applying the brake mechanism, the worm 68 may be given a powerful rotary movement at a comparatively rapid rate, but when the brake is partially released so as to permit slipping to a regulated degree, a slower rate of movement may be obtained, although also very powerful. The slow and powerful feeding movement of the cutting apparatus may therefore be regulated by the extent to 130

which the brake mechanism is applied, and when the cutting apparatus is to be returned to initial position, the brake may be fully applied so as to secure the maximum speed 5 of return movement.

When it is desired to raise or lower the mining machine the pin 61 is withdrawn from the opening 62 in the worm nut 56 and the worm nut is driven by means of the 10 mechanism described. The rotation of the worm nut on the standard 53 will cause the nut to be moved upwardly or downwardly along the standard, depending on the direction of rotation of the motor 65. In this 15 way the mining machine frame-work may be adjusted vertically to any desired position on the upright 53. It will be seen that the vertical adjustment on the upright 53 will produce a pivotal movement about the 20 supports 23. This will vary the position of the lower end of the standard 53 somewhat causing the block 52 to slide on the guide-way 51.

If the worm nut 56 is locked from rotation 25 on the standard 53 by means of the washer 57 and pin 61 rotation of the shaft 68 will no longer rotate the worm nut 56 on the screw 55 but the worm nut will be held rigidly from rotation since the standard 53 is 30 prevented from rotation by the pivot pin 54. When the parts are in this relation therefore operation of the motor 65 will cause the worm 68 to walk around the periphery of the worm nut 56 and carry with it the entire 35 frame work on which the worm 68 is mounted. By this method the frame work is rotated to feed the cutting mechanism of the mining machine into the work, as will be more fully explained.

40 Carried by the supports 35 and 36 at the upper and lower portions thereof respectively, are two bearings 70 and 71. These bearing rings are split on a line transversely of the machine and are provided 45 with removable portions, as shown in Fig. 7, and held in place by bolts 72. The bearings 70 and 71 are each provided with two separate rings, the larger one of which, as shown in Fig. 6, is in axial alignment 50 with the sleeve 37. The smaller bearing ring of the bearings 70 and 71 is offset laterally, as shown in Fig. 7, and carries a vertical shaft 73. The upper bearing 70, as shown in Fig. 6, is provided with a 55 bushing 74 in which a hollow drum 75 is journaled for rotation. The drum 75 carries a spur gear 76 at its lower end and a sprocket wheel 77 at its upper end. The lower bearing 71 carries a similar drum 78 which has a spur gear 79 at its upper end 60 and two sprocket wheels 80 and 81 at its lower end. The vertical shaft 73 (Fig. 7) is provided at its upper end with a pinion 82 which meshes with the gear 76 and at its lower end with a corresponding pinion 83

which meshes with the gear 79. The shaft 73 is driven by a worm wheel 85 (Fig. 5) meshing with a worm 86 carried on the motor shaft 66. A clutch 87 (Fig. 7) operated by a lever 88 is provided for connecting and disconnecting the shaft 73 with the worm wheel 86.

For severing the material from the mine wall a system of cutter chains is provided supported and guided by a cutter chain 75 frame-work best illustrated in Figs. 4, 5, and 6. This frame-work comprises an upright bar 90 carrying horizontally extending bars 91 and 92 at its upper and lower end, respectively. The rear portion of the 80 upper bar 91 is provided with a downwardly projecting plate 93 which fits between guideways 94 in the upper portion of the supports 35 and 36. A downwardly projecting lug 95 is secured to the lower 85 surface of the plate 93 and the support 35 is provided with a cooperating lug 96. A threaded rod 97 connects the lugs 95 and 96 and is arranged to adjust the plate 91 longitudinally relative to the guides 94. 90 In a like manner the lower bar 92, as shown in Figs. 6 and 10, is provided with an upwardly extending guide plate 98 which fits between guides 99 carried on the supports 35 and 36. An adjusting screw 100 similar 95 to the screw 97 is provided for the lower cutter bar 92. As shown in Figs. 5 and 6, the lower cutter bar 92 is provided with a guide flange 101 which extends around the entire outer periphery thereof. A cutter 100 chain 103 is supported by the guide flange 101 on the outer periphery of the bar 92. The chain 103 at its inner end passes around the sprocket wheel 80 and is driven thereby by means of the gear 79 and shaft 73. In 105 a similar manner an upper cutter chain 104 is mounted on the upper bar 91 and is driven by the sprocket wheel 77 supported in the upper bearing 70. It will be apparent that the entire cutter frame comprising the bars 90, 91 and 92 may be moved toward and from the sprocket wheels 77 and 80 to adjust the tension in the chains 110 103 and 104.

The bars 91 and 92 are each provided 115 with central longitudinal slots 105 and 106 respectively. As shown in Fig. 5 these slots extend throughout the greater part of the outer portion of the bars and are provided at one side thereof with chain guides 107. A vertically extending bar 108 (Figs. 3 and 5) connects the outer ends of the horizontal bars 91 and 92 and is secured in these bars by arcuate members 109 forming rounded corners between the vertical and the horizontal bars. The chain guide 107 is continued around the corner members 109 and extends vertically along the bar 108, as shown in Fig. 5. In this way a loop 125 guide is provided over which a cutter chain 130

- 110 passes in the form of a loop, as shown in Fig. 6. Curved corner plates 111 are positioned to guide the chain past the upper and lower ends of the upright 90.
- 6 From the corner plates 111 the chain 110 passes inwardly and around a sprocket wheel 112 secured to the shaft 45 supported in the bearings 43 and 44. The chain 110 is of sufficient length to permit a slight 10 dip in the loose run thereof above the sprocket wheel 112. This gives the chain a longer bearing on the sprocket wheel and also avoids the necessity for providing means for adjusting the tension of the chain.
- 15 The sprocket wheel 112 and the chain 110 are driven by means of a worm 113 secured to the shaft 66, as shown in Fig. 5. A clutch operated by a handle 114 is provided for making and breaking the driving connection between the shaft 66 and the chain 110.
- 20 In Fig. 5^e I have shown a clutch element 206 splined to the shaft 45 so as to be slideable into engagement with the clutch element at the outer end of the hub 207 of the worm wheel 208 which meshes with the worm 113 mounted on the shaft 66. The lever 114 may be pivoted at 209 to suitable brackets 210 extending laterally from the 25 worm gear casing 211. It will thus be seen that when the clutch 206 is thrown in by means of the lever 114, motion will be transmitted from the shaft 66 to the shaft 45 so as to rotate the sprocket wheel 112 shown in Fig. 6, as well as in Fig. 5.
- 30 The arrangement of cutter chains described is especially useful in mining hard material such as hard coal. In mining material of this character some difficulty has 35 been experienced in using a single loop cutter. The present invention overcomes this difficulty by providing independent chains for making the horizontal cuts at the upper and lower portions of the material being 40 cut. This leaves only the vertical cut to be made by the loop chain since the horizontal portions of this chain will travel in the kerf already formed by the horizontal cutter chains. The particular arrangement of the 45 chains relative to one another makes it possible to operate all of the chains by a single operating mechanism, and to support all of the chains on a single cutter frame. By this arrangement the frame may be made stronger and more efficient than would be the case 50 if separate guide frames were provided for the different machines. The upright connection for guiding the vertical run of the loop cutter forms a brace for the outer ends 55 of the horizontal cutter arms and the horizontal cutter arms in like manner form a substantial support for the horizontal runs of the loop cutter. The cutter chains are fed into the work by the rotary movement 60 of the cutter head about the support 53 pro-
- duced by the rotation of the worm 68 in contact with the worm 56 in the manner already described. The cutter is arranged to make a crescent-shape cut in a mine wall, as shown in Figs. 1 and 3.
- 65 For the purpose of removing the coal severed from the mine wall by the cutter chains novel mechanism is provided, as will be understood by reference to Figs. 4, 5, 7, 8^a and 9. Supported on the periphery of the table 46 are a plurality of short pivoted links 120. Pivotedly carried by the outer ends of the links 120 is a vertically extending horizontally curved guard plate 121, and extending horizontally from the lower edge 70 of the plate 121 is an arcuate table 122. The upper surface of the table 122 is serrated, as shown in Fig. 9, with the teeth of the serrations pointing rearwardly or away from the cutter frame. Mechanism to be described is provided for swinging the table 122 on its supporting links 120 to give it a reciprocatory motion toward and away from the cutter frame. The driving mechanism is so arranged that a quick movement toward the cutter is produced while the movement away from the cutter is relatively slow. The effect of this reciprocatory movement will be to slide the table quickly under the material that has been severed by the cutter, the inertia of the severed material holding it in place while the table is moved beneath it. On the slower return movement, however, the severed material will be carried back by the serrations on the surface 75 of the table and will be eventually discharged from the table at the rear end thereof. It should be noted that the table 122 is of less extent angularly than the arc through which the cutter frame travels during a single operation. This feature is desirable in order that the cutter head, including the cutter frame and the table, may be 80 swung backwardly a sufficient amount to permit the cutter to be properly positioned to begin a cutting operation. If the table were made of sufficiently angular extent to receive an entire section severed by a cutting operation it would be difficult to get the cutter head into its initial position for 85 starting a cutting operation because of the fact that the rear end of the table would be swung into position to strike either a part of the machine frame or if the frame were so 90 designed as to leave a free path for the table the rear end of the table would then swing into position to strike the portion of the wall that is severed during the last part of the cutting operation. It can be readily seen, therefore, that a table of comparatively 95 small angular extension is desirable, and this is made possible in the present invention by the fact that the table is operated to discharge the material as it is severed from the mine wall and it is therefore not 100
- 105 110 115 120 125 130

necessary for the table to be of sufficient extent to receive the entire body of severed material. After the cutter frame and the table 122 have reached approximately mid position, as shown in Fig. 4, the reciprocation of the table may be discontinued, if desired, and the material severed during the latter portion of the cutting operation may be allowed to remain on the table until the 10 cutter frame is swung backwardly for a new stroke. If this is done the material on the table 122 will be carried backwardly at the same time that the cutter frame is moved to its initial cutting position and the 15 material may then be discharged into the conveyor at the discharge side of the machine. It is not necessary to operate the table in this way, however, but the reciprocating movement may be continued through 20 out the entire cutting operation. If this is done a part of the severed material during the latter portion of the cutting operation will be discharged from the table 122 at a distance considerably removed from the 25 receiving end of the transportation conveyor. This material will be picked up, however, during the backward movement of the cutter frame and will then be carried to a position where it may be dis- 30 charged on to the transportation conveyor. As previously stated, the worm 68 for rotating the cutter head about the support 53 may be given either of two operating speeds; the slower speed will be used during the 35 forward movement of the cutter frame and the rapid movement may be used during the return operation. For reciprocating the table 122 a lever 123 is pivotally mounted at 124 on the table 46. The outer end of the 40 lever 123 has pivotally secured thereto a link 125 which has one end pivoted to the guard plate 121 at 126. The inner end of the lever 123, as shown in Figs. 7 and 8^a, is provided with two prongs 126' and 127. 45 The prong 127 is offset downwardly and engages a cam 128 mounted on the vertical shaft 73. The prong 126' engages a cam 129 of a different shape which is integral with the cam 128. The cams 128 and 129 are 50 normally free to rotate on the shaft 73 but may be clutched thereto by a clutch 128' operated by a handle 129' pivotally supported from the lower surface of the table 46, as shown in Fig. 7. A bar 126'' is secured 55 to the table 46 and passes over the top of the cam 128, as shown in Fig. 7, for preventing upward movement of the cam when the clutch 128' is operated. When the shaft 73 is rotated in a clockwise direction, as viewed 60 in Fig. 8^a, the forked end of the lever 123 will be driven by the cam 128 with a comparatively slow movement to the right during a half revolution of the shaft. On the second part of the rotation of the shaft 73, as 65 however, the forked end of the lever will be given a rapid movement in the opposite direction, being driven by the cam 129. This produces a rapid forward movement of the table 122 which is followed by the slow return movement produced by the cam 128. 70

To prevent the severed coal from contacting with the operating mechanism a guard wall 130 is positioned at the inner edge of the table 122, the wall passing just outside of the upstanding plate 121 to which the plate 122 is secured. The guard wall 130 has its lower edge sufficiently raised above the base 32 to permit the cutter frame to swing beneath the wall, as shown in Fig. 6. The wall is supported by brackets 131, 132 and 133, which are secured at their rear ends to the upstanding portion of the tilted frame 24 through which the pivotal supporting pin 28 passes, as shown in Fig. 4. The base member 25, as represented also in Fig. 4, 80 has a pivoted extension plate 134 and the wall 130 has a hinged extension 135 which extends over the plate 134 and is held in place by a removable link 136. The purpose of the extension 135 is to prevent coal which is severed during the latter portion of a cut from falling away from the position it occupied forwardly out of the path of the table 122. The hinged extensions 134 and 135 may be folded inwardly to permit 85 easy transportation of the machine when occasion requires. 90

The cutter chains when in operation remove considerable loose material in the form of coal cuttings or culm and this material is constantly drawn backwardly by the chains on to the rotary plate 32. In order to carry this material backwardly to a transporting conveyor a chain 137 provided with flights 138 passes around the sprocket wheel 81 and extends backwardly as shown in Figs. 5, 6 and 8, over a guide wheel 139 mounted at the rear portion of the machine. As 100 shown in Fig. 5 the ring 33 is discontinued to form openings 140 through which the chain 137 passes. A cover plate 141 is secured to the ring 33 to overlap the openings through which the chain 137 passes. The rear portion of the base plate 25 is provided with grooves 142 in which the chain 137 travels, and a plate 143 is fastened to the base plate 25 to form a cover for the chain 137. The coal cuttings or culm carried 105 backwardly by the chain 137 is discharged at the end of the chain into the same conveyor that carries away the coal from the table 122. 110

In order that the base plate 25 of the machine may fit tightly against the surface of the wall made by the last preceding cut this plate is provided with an adjustable extension 145 which fits in a groove 146 extending along the side edges of the main base plate 25 and the arcuate front portion thereof, as 115 best shown in Figs 6, 7 and 8. The hinged 120

125

130

extension 134 is attached to one side of the adjustable member 145, as shown in Fig. 8. The rearwardly extending arms of the extension 145 are connected by a cross bar 147, as shown in Fig. 6, and in broken lines in Fig. 8. A spring 148 has a plunger 149 which engages the cross bar 147 and normally tends to force the plate 145 forwardly. When the machine is moved forward to a new position the front edge of the extension 145 will first come into contact with the surface formed by the last preceding cut and will form a tight connection between the base plate of the mining machine and the mine wall and prevent any particles of coal from dropping downwardly between the wall and the edge of the base plate. The spring 148 will hold the plate 145 resiliently against the wall and thus provide for any slight inaccuracy in the positioning of the machine.

As shown in Figs. 1 to 4 inclusive, the lower end of the mining machine frame from which the material is discharged overlies the receiving end of a conveyor 150 supported for horizontal pivotal movement on a rearwardly extending portion of the base member 21. The material as it is carried backwardly and discharged from a mining machine is received upon the conveyor 150 which may be driven, as shown in Fig. 1, by a motor 151 and which carries the material to a position to be discharged into cars or other transporting mechanism. The relation of the mining machine proper to its conveyor, as indicated in Figs. 1 and 2, is such that the conveyor may be swung into various angular positions relative to the direction of movement of the mining machine in a mine chamber. This enables the operator to change the direction of an entry being driven by the machine without disturbing the relation between the machine and the conveyor. For instance, the machine may have been previously driving an entry in the direction of the broken line position of the conveyor in Fig. 1 and have been changed to the direction in which the entries were driven with the machine in the position shown in that view. This change in the direction can be accomplished while the material continues to be removed along the old entry, as will be apparent from an inspection of Fig. 1.

In the modification of the invention shown in Figs. 12 to 14 inclusive, the general construction is similar to that previously described. In the modified form, however, the rear end of the machine is pivotally carried by sliding blocks 160 carried in upright frame members 161 and provided with threaded adjusting rods 162. The threaded rods 162 have beveled pinions 163 meshing with pinions 164 carried on a horizontal shaft 165. The shaft 165 is driven by a

motor 166 connected to the shaft through a worm gearing 167. Where this construction is used the brackets 168 which carry the pointed anchor rods for contacting with the roof of the mine chamber to hold the machine in place are offset as shown in Fig. 12 so that the anchor rods will not interfere with the support for the adjustable pivot. As will be seen from Fig. 13, when this form of the invention is employed the cutting mechanism may be moved bodily to its upper position so that the upper cutting chain will cut the coal from the roof of the mine with a smooth cut in an approximately horizontal plane instead of leaving portions of the coal adhering to the roof as is done where the cutting head is tilted about a stationary pivot into its upper cutting position.

The table 170 employed in the form shown in Figs. 12 and 13 is slightly different from that of the other views in that it is not given a short reciprocatory movement but is fed forwardly with the cutter frame until a portion of the material being severed has become detached from the mine wall. The table is then moved backwardly carrying with it the severed material which is discharged from the table while in its retracted position. The table is then moved forwardly and receives another portion of severed material, the operation being repeated as many times as is necessary to carry back the material severed by a complete cut. The table is pivotally connected by an arm 171 to the central vertically extending sleeve 172 which corresponds to the sleeve 37 of the form previously described. The table 170 is supported beneath the shelf 173 which carries the motor and other operating mechanism in a manner similar to that described in connection with the other form of the invention. The arm 171 is held to the lower end of the sleeve 172 for pivotal movement thereon by a flat ring 174 and lag screws 175. A threaded standard 176 extends through the sleeve 172 in a manner similar to the standard 53 in the previously described form of the invention. The inner edge of the table 170 is provided with a flange ring 177 which carries rollers 178 arranged to travel on a flat ring 179 corresponding to the ring 33 of the previously described form. The ring 177 is provided throughout the greater part of its length with rack teeth 180 arranged to mesh with a pinion 181 driven by a motor 182. By means of this motor and the gearing described the table 170 is operated for transferring the coal from its severed position to its discharging position. A scraper 183 is provided for removing the coal from the table 170 as the table is moved forward at each operation to receive a new load. This scraper 183 is pivoted at 184 and is provided with a toe 185 which strikes against

the abutment plate 186 to limit the forward movement of said scraper to its full line position shown in Fig. 12. The scraper is free to be swung backward by the backwardly moving load, but when the latter starts forward again the scraper 183 automatically engages the load and prevents it from moving forward with the rotary carrier 170. On the next retraction of the latter with a load the previous load is pushed along into the hopper and onto the pivoted rear conveyor.

10

I claim:

1. In a mining machine, the combination with a main supporting frame, of a supplemental frame pivotally connected at its rear portion to said main frame in a relatively low position, means mounted on the forward end of said supplemental frame for dislodging material from an upright mine wall, a supplemental support connected to said supporting frame in position to extend forwardly therefrom along the floor of the mine chamber, means connected between

20 such forward extension and said supplemental frame for assisting in supporting the latter, and means for adjusting the height of said adjusting mechanism by swinging said supplemental frame on its pivotal support relatively to said main frame.

25

2. The combination with a supporting frame having a narrow forward extension at its lower portion, of a mining machine pivotally connected at its rear portion to said supporting frame, means connected directly between said narrow extension and the forward portion of said mining machine for supporting the latter in an elevated position on said extension, and mechanism for adjusting the elevation of the forward portion of said mining machine.

30

3. The combination with a supporting frame having a lower forward extension, of a mining machine pivotally connected to said supporting frame and extending forwardly over said extension, an auxiliary support connected to said mining machine, and a slideable connection between said auxiliary support and said forward extension.

35

4. The combination with a supporting frame comprising upright spaced apart standards and a lower forward extension adapted to occupy a position substantially at the floor of a mine chamber, of a mining machine pivotally connected at its rear end portion between said standards and extending forwardly over said extension, an upright standard connected between the forward lower portion of said mining machine

40 and the forward upper side of said extension, and means for adjusting said mining machine on said upright standard relatively to said forward extension and moving said mining machine about its pivotal support as an axis.

45

5. The combination with a supporting frame comprising spaced apart upright standards and a lower forward extension, of a mining machine pivotally connected at its rear end portion between said upright standards and extending forwardly above said extension, means for supporting said mining machine above said forward extension, said last-named supporting means being connected between the forward end portion of said extension and the bottom side of said mining machine intermediate its ends, and means associated with said last named supporting means below the top of the mining machine for lifting and lowering the forward end of said mining machine while the rear portion thereof is supported by said pivotal connections to said upright standards.

50

6. The combination with a supporting frame having a forward extension adapted to rest on the floor of a mine chamber, a mining machine pivotally connected at its rear end portion to said supporting frame and extending forwardly therefrom over said extension, and a supplemental support for said mining machine pivotally and slidably connected to said extension.

55

7. The combination with a supporting frame having a forward extension extending over the mine floor and along the same, of a mining machine pivotally connected at its rear end portion to said supporting frame, a supplemental support for said mining machine, a slide block pivotally connected to the lower end of said supplemental support, and means for guiding said slide block forwardly and rearwardly on the forward end portion of said extension while preventing lateral movement of said supplemental support relatively to said extension.

60

8. The combination with a supporting frame comprising spaced apart upright standards and a forward central extension, of means for anchoring said supporting frame between the floor and roof of a mine chamber with said extension projecting forwardly over the mine floor, a mining machine pivotally connected at its rear end portion between said upright standards and extending forwardly along said extension and above the same, an upright standard connected between the forward end portion of said extension and the lower side of said mining machine intermediate its ends, and means associated with such upright standard for adjusting the elevation of said mining machine while being pivotally supported at its rear end by the pivotal connection in said spaced apart standards and while being supported at its forward portion by said upright standard.

65

9. In a mining and loading machine, the combination with a supporting frame, of a conveyor pivotally connected to said sup-

porting frame in position to extend into a mine car on a mine track while said supporting frame is adapted to swing angularly to various adjusted positions on the mine floor, 5 a supplemental frame mounted on said supporting frame to extend in a general horizontal direction in a mine chamber between the floor and roof thereof, cutting mechanism mounted on the forward portion of 10 said supplemental frame in position for operating on the upright mine wall between said floor and roof, and mechanism for delivering cut material from the mine wall to said conveyer in the various positions to 15 which said supporting frame is adjusted on the mine floor while said conveyer remains in position to deliver material to a mine car on the same mine track.

10. The combination with supporting 20 frame-work approximately circular in plan, of core cutting mechanism mounted on said framework, means for operating said core cutting mechanism to cut crescent-shaped cores from a mine wall adjacent said framework and said cutting mechanism being readily shiftable to vary the direction of the movement of the cutting mechanism to a new position, a conveyer connected to 25 said framework for movement horizontally about one end of said conveyer to various angular positions relatively to said framework, and mechanism for delivering the cut material to the conveyer in its various angular positions relative to said framework.

11. The combination with a supporting frame adapted to rest on the floor of a mine chamber, of a supplemental frame mounted on the forward portion of said supporting 40 frame and extending forwardly therefrom, said supplemental frame being approximately circular in plan, of core cutting mechanism mounted on said supplemental frame, means for operating said core cutting mechanism to cut a crescent-shaped core of material from a mine wall in a general horizontal direction, means for transferring the core of material from the mine wall along said supplemental frame over the rear 45 discharge end thereof, and a conveyer pivotally connected to the rear portion of said supporting frame for angular adjustment horizontally relative to said supporting frame without altering its receiving position 50 relative to the discharge end of said supplemental frame.

12. In combination, a mining machine head, a loop core cutter carried by said head for movement about an upright axis, an 60 arcuate table, means for moving said table in the kerf formed by said cutter, and means for reciprocating said table to transfer material severed by said cutter while said table remains in position in the cut made by said 65 cutter.

13. In combination, a mining machine frame, a cutter head carried by said frame, a loop core cutter carried by said cutter head for rotation about an upright axis, an arcuate table of less extent angularly than the 70 angular rotation of said cutter during a cutting operation, and means for operating said table relatively to said cutter to remove the material severed by said cutter a part at a time.

14. In combination, a mining machine frame, a cutter head having a loop core cutter carried by said frame, an arcuate carrier having an angular extension of less than 180°, and means for moving said carrier independently of the movement of said cutter including movement of the carrier into the kerf formed by said loop cutter to receive a load of material.

15. In combination, a mining machine 85 frame, a cutter head having a loop core cutter carried by said frame, an arcuate table carried by said cutter head and movable into the kerf formed by said loop cutter, and means for imparting short reciprocations to 90 said table relative to said cutter head.

16. In combination, a mining machine frame having a cutter head provided with a loop cutter, a table for receiving material severed by said cutter, links for movably securing said table to said cutter head, and means for imparting short reciprocatory movements to said table, the movements of said table in one direction being comparatively rapid and in the other direction comparatively slow.

17. In combination, a mining machine frame, a cutter head carried by said frame, core cutting mechanism carried by said cutter head, means for receiving material disconnected by said severing mechanism, said receiving means being arranged to transport said material while said means remains in receiving position.

18. In a mining machine, the combination 110 with a supporting frame, of core cutting mechanism having an unobstructed core opening therethrough and mounted on said frame for arcuate movement relatively thereto on an upright axis, means for operating 115 said core cutting mechanism including arcuate feeding movement thereof on such upright axis while said frame remains in stationary position to effect the cutting of a core in a general horizontal direction, a device mounted on said frame for movement 120 relatively thereto in position to extend into the kerf formed by said cutter for receiving the core material, and means for operating said device while in receiving position for 125 transporting the material received thereon.

19. In combination, a mining machine frame, a loop core cutter carried by said frame for rotation about an upright axis, a device for receiving material severed by said 130

cutter, means for moving said device into the kerf formed by said cutter during a cutter operation thereof, and means for operating said device while in receiving position for 5 transferring material received thereon.

20. In combination, a mining machine frame, a cutter head carried by said frame for rotation about an upright axis, a loop core cutter carried by said cutter head, an 10 arcuate table carried by said cutter head and having its forward end positioned adjacent the rear portion of said loop cutter, and means for imparting a reciprocatory movement to said table relatively to said cutter head to transfer material received on said 15 table.

21. In a mining machine, the combination with a supporting frame, of mechanism mounted thereon for movement relatively 20 thereto to dislodge material from an upright mine wall, a ring sector plate mounted on said frame for movement relatively thereto with its upper surface in a generally horizontal position to receive the severed material 25 and carry the same by gravity on such upper surface, and means for operating said sector plate for transferring severed material toward loading position while said plate remains in receiving position.

22. In a mining machine, a cutter, means for operating said cutter to sever material from its native bed, a table for receiving the material so severed, means for rotating said table and said cutter about a common 35 axis, and means for imparting a reciprocatory movement to said table independent of said rotation about said axis.

23. In combination, a mining machine frame, a cutter mounted on said frame for 40 rotation about an upright axis, an arcuate table, means for moving said table about the axis of said cutter into the kerf formed thereby, and means for imparting a reciprocatory movement to said table independent 45 of said rotation about said axis to operate said table to transfer material thereon while said table remains in position adjacent said cutter.

24. In a mining machine, a cutter head 50 rotatable about an upright axis, severing mechanism carried by said cutter head, a table for receiving material disconnected by said severing mechanism from its native bed, links connecting said table to said cutter 55 head to permit said table to reciprocate relative to said cutter head, and mechanism for imparting a rapid movement of said table relative to said cutter head toward said severing mechanism, and a slower movement 60 of said table in an opposite direction.

25. In combination, a supporting frame, a cutter head carried by said frame for rotation about an upright axis, a cutter secured to said cutter head for rotation therewith,

an arcuate table carried by said cutter head, 65 and having its forward end positioned adjacent to the rear portion of said cutter, links connecting said table with said cutter head and arranged to permit reciprocatory movement of said table relative to said cutter head, and mechanism for operating said table and arranged to impart a rapid movement of said table toward said cutter and a slower movement to said table in an opposite direction. 70

26. In a mining machine, the combination of a core cutter having a single cutter frame with an unobstructed core opening therethrough, and a plurality of spaced apart plane kerf cutters carried by said frame in 80 position to assist said core cutter in cutting a core extending through such unobstructed core opening and through the space between said spaced apart plane kerf cutters.

27. In a mining machine, a loop cutter 85 comprising a U-shaped frame, a cutter chain carried by said frame for severing material along the exterior portion of said frame, and separate cutter chains for forming a kerf for the inward and outward runs of 90 said first mentioned chains.

28. In a mining machine, a loop core cutter comprising a frame movable about a central axis, a cutter chain for forming a kerf at a portion of said frame removed 95 from said axis, and a separate chain for forming a kerf extending away from said axis toward said exterior portion of said frame.

29. In a mining machine, a loop cutter 100 comprising a U-shaped frame movable about a central axis, a cutter chain for severing material along the portion of said frame removed from said axis, and separate cutter chains for severing material along the portion 105 of said frame extending between said axis and said removed portion.

30. In a mining machine, the combination with a cutter frame having an unobstructed core opening therethrough, of a chain cutter 110 mounted on said cutter frame to travel around said unobstructed core opening transversely of the direction of feed of said cutter frame, and spaced apart chain cutters mounted on said cutter frame to travel about 115 spaced apart portions thereof in spaced apart planes parallel to the direction of feed of said cutter frame.

31. In a mining machine, a loop cutter 120 comprising a U-shaped frame movable about a central axis, a cutter chain for severing material along the portion of said frame removed from said axis, and separate cutter chains for forming kerfs in which the inward and outward runs of said first mentioned chain move. 125

32. In a mining machine, a cutter frame provided with a cutter arm having a slot

therein, a cutter chain carried by said arm in position to form a kerf therefor, and a second cutting mechanism including a cutter chain movable in said slot.

5. 33. In a mining machine, a cutter frame having an arm, a cutter chain carried by said arm for severing material to form a kerf in which said arm travels, a guide-bar carried by said arm and extending angularly 10 therefrom, and a second cutting mechanism including a cutter chain movable along said guide-bar during a portion of its travel and movable in the kerf formed by said first cutter chain during another portion of its 15 travel.

34. In a mining machine, a cutter comprising a single frame, a plurality of chains carried by said frame and so arranged that one of said chains travels in the plane of 20 another of said chains and within the boundary of the latter during a portion of the travel of said first mentioned chain.

35. In a mining machine, a cutter frame, a support for said frame, a core cutter chain 25 carried by said frame, and a plane kerf cutter carried by said frame and arranged to form a kerf in which said chain moves during a portion of its travel.

36. In a mining machine, a loop cutter 30 comprising a frame, a pair of arms having slots therein and a bar connecting said arms, a cutter chain movable along said bar for forming a kerf in material to be mined but movable in the slots in said arms during a 35 portion of its run, and independent cutter chains for forming kerfs for said arms.

37. In a mining machine, a loop cutter comprising a cutter frame having substantially parallel arms connected at their outer 40 ends by a guide bar, a cutter chain movable along said connecting guide bar for forming a kerf in material to be severed and movable in slots in said arms toward and away from said guide bar, and independent cutter 45 chains carried by said arms for forming kerfs in said material through which said arms may move.

38. In a mining machine, the combination with cutting mechanism, of a base plate 50 for receiving cut material, and a resiliently movable extension for said base plate arranged to contact with the wall of a mine chamber to make close connection between said wall and said base plate.

55. 39. In a mining machine, the combination with cutting mechanism, of a platform for receiving cut material, an extension carried by said platform for sliding movement relative thereto, and a spring for holding said extension resiliently in contact with the wall 60 of the mine chamber.

40. In a mining machine, the combination with cutting mechanism, of a platform having an arcuate periphery, an extension plate

fitted to said periphery and arranged to 65 contact with the wall of a mine chamber, and resilient means for forcing said extension plate into contact with said wall.

41. In a mining machine, a platform having a groove in the periphery thereof, an 70 extension plate supported in said groove for contacting with the wall of the mine chamber, and a spring for forcing said extension plate into contact with the wall of said chamber. 75

42. In a mining machine, the combination with a supporting frame, of a loop chain core cutter mounted on said frame and having an unobstructed core opening therethrough, a plane kerf cutter associated with the lower run of said loop chain core cutter, and means mounted on said frame in position to receive the cuttings from both said loop chain core cutter and said plane kerf cutter and transfer such cuttings toward 80 loading position.

43. In a mining machine, the combination with a supporting frame, core cutting mechanism having an unobstructed core opening therethrough and mounted on said 90 frame for swinging feeding movement on an upright axis, loading apparatus for transferring the cut core material from the mine wall toward loading position, said loading apparatus comprising a ring sector 95 plate mounted on said frame in position to extend under the core material, and a conveyor on said frame traveling over a position adjacent the lower inner portion of said core cutting mechanism for receiving 100 the cuttings from the latter during its arcuate feeding movement about the said upright axis and transfer such cuttings away from the mine wall.

44. In a mining machine, the combination with a supporting frame comprising a platform, of loop chain core cutting mechanism mounted on said frame with its lower run traveling toward said platform and adjacent the forward end thereof, a 110 plane kerf cutter associated with said lower run, and a conveyor movable over said platform to remove the cuttings deposited by said loop chain core cutting mechanism and by said plane kerf cutter and transfer such 115 cuttings toward the rear portion of said supporting frame.

45. In a mining machine, the combination with a supporting frame, of core cutting mechanism having an unobstructed core opening therethrough and mounted on said frame in position to cut a single core extending in a generally horizontal direction through said unobstructed core opening, a plane kerf cutter associated with 120 said core cutting mechanism, and a conveyor mounted on said frame in position to receive the cuttings from said core cutting 125

mechanism and from said plane kerf cutter and transfer such cuttings toward loading position.

46. In a mining machine, the combination with a supporting frame, of a base plate mounted thereon, a standard mounted on said base plate, cutting mechanism carried by said standard, a supporting screw for said standard, an adjustable nut carried by said screw and arranged to support said standard and said base plate, and means mounted on said supporting frame for holding said base plate and said standard from tipping relatively to said supporting frame.

47. In a mining machine, a frame, means for pivotally supporting said frame at one end thereof, a circular plate rotatably mounted in said frame at the other end thereof, cutting mechanism carried by said plate, a standard connected with said plate, and means for adjusting said plate and cutting mechanism on said standard.

48. In a mining machine, a circular plate, a frame carried by said plate, severing mechanism mounted on said frame, a standard for supporting said frame and severing mechanism, means for adjusting said frame along said standard, means for rotating said frame relative to said standard, and means for cooperating with said plate to prevent tipping of said frame and severing mechanism.

49. In a mining machine, a frame pivotally supported at one end thereof, a circular guideway at the opposite end of said frame, a plate rotatably mounted in said guideway, frame members secured to said plate, severing mechanism carried by said frame members, a standard projecting through said plate and connected with said frame members, and means connected with said standard for adjusting said severing mechanism along said standard and for rotating said severing mechanism about said standard as an axis.

50. In a mining machine, the combination with a cutter frame, of a chain cutter mounted on a portion of said cutter frame to travel around the same in position to cut a plane kerf in a mine wall, an additional chain cutter mounted on said frame to travel about another portion thereof having an unobstructed core opening extending therethrough, means comprising a drive wheel mounted for rotation on a horizontal axis to actuate said core chain cutter, mechanism comprising a drive wheel mounted for rotation about an upright axis to actuate said plane kerf cutter, means for controlling the actuation of each of said chain cutters independently of the other, a supporting frame for the aforesaid parts, and means for effecting feeding movement of said first named frame during

the actuation of said chain cutters to cause said chain cutters to cut a core of material in a mine wall in a general horizontal direction.

51. In a mining machine, the combination with a supporting frame, of a chain cutter drive wheel mounted on said frame for rotation about a horizontal axis, a pair of chain cutter drive wheels mounted in spaced apart relation on said frame for rotation about a common upright axis, three chain cutters connected respectively to said drive wheels for actuation thereby, and a cutter frame common to said chain cutters for guiding the latter for actuation by the respective drive wheels, said common cutter frame having an unobstructed core opening therethrough, and means for operating said chain cutters including feeding movement of said common cutter frame and actuation of said chain cutters by means of said drive wheels to effect the cutting of a core of material extending through said unobstructed core opening.

52. In a mining machine, the combination with a cutter head, of a core cutter carried by said cutter head and comprising a frame, a chain guided on said frame in an upright loop having an unobstructed core-opening therethru, a second chain in the plane of a predetermined run of said first named chain and surrounding such predetermined run, and means for operating said chains.

53. In a mining machine, a cutter head, a loop cutter for said cutter head comprising an upright rectangular frame member, a cutter chain guided in an upright loop about said frame member, independent cutter chains guided in horizontal loops on the upper and lower portions of said frame member, and drive wheels for operating said cutter.

54. In a mining machine, a cutter head provided with a loop core cutter comprising a substantially rectangular closed frame member having an unobstructed core opening therethrough, and a plurality of endless chain cutters carried by said frame member and arranged to travel in planes arranged in different angular positions relative to one another.

55. In a mining machine the combination a cutter head, of a core cutter mounted on said cutter head and comprising spaced apart plane kerf cutters and an intermediate loop chain cutter having an unobstructed core-opening therethru, and means for operating said core cutter.

56. In a mining machine, a cutter head, a loop cutter for said cutter head provided with a cutter frame, endless chain cutters carried by said cutter frame and arranged in planes substantially at right angles to one another, drive wheels for said cutter chains, and means for changing the position of said

1 cutter frame relative to said cutter head for adjusting the tension in some of said cutter chains.

57. In a mining machine, the combination with a supporting frame, of a mining machine frame pivotally supported at one end thereof on said supporting frame, a standard projecting upwardly from the forward portion of said supporting frame, a cutter head, means for supporting said cutter head on said upwardly projecting standard for adjustment vertically on said standard, and means for connecting said cutter head to said mining machine frame for holding said cutter head from tipping relatively to said mining machine frame.

58. In combination, a mining machine frame, means for pivotally supporting said frame at one end thereof, a cutter head located at the end of said frame opposite said pivotal support, an upright standard, means for supporting said cutter head on said standard, means for adjusting said cutter head vertically along said standard, means for rotating said cutter head about said standard, and means for rotatably connecting said cutter head with said mining machine frame.

59. In combination, a mining machine frame, a cutter head rotatably secured to said mining machine frame, an upright sleeve forming part of said cutter head, a supporting standard positioned in said sleeve, a nut carried by said standard for supporting said sleeve, means for rotating said nut relative to said standard for adjusting said sleeve and cutter head vertically, means for securing said nut against rotation relative to said standard, and means cooperating with said nut for rotating said cutter head relative to said standard.

60. In combination, a mining machine frame, means for pivotally supporting said frame at one end thereof, a cutter head carried by said frame at the other end thereof and rotatably secured thereto, a standard for supporting said cutter head, a sleeve carried by said cutter head in which said standard is positioned, a nut threaded on said standard, means for rotating said nut to adjust said cutter head vertically along said standard, and means for holding said nut against rotation to cause said cutter head to rotate in said mining machine frame and about said standard as an axis.

61. In a mining machine, the combination with a base frame having rigidly connected thereto a forward extension adapted to be located substantially on the floor of a mine chamber, of means for engaging the roof of a mine chamber for holding said base frame including said forward extension firmly in adjusted position, a main frame adjustably mounted on said base frame, cutting appara-

tus mounted on said main frame and movable bodily up and down therewith, means mounted directly on said forward extension in position to support the forward portion of said main frame and the cutting apparatus, and mechanism for adjusting the height of said cutting apparatus.

62. In a mining machine, the combination with a base frame having a forward extension and upright standards, of a main frame pivotably and slidably connected to said upright standards, cutting apparatus carried by the forward portion of said main frame a support for the forward portion of said main frame, a pivotal and slidable connection between said last-named support and said forward extension, and means associated with said support for adjusting the height of said cutting apparatus.

63. In a mining machine, the combination with cutting apparatus, of supporting frame-work therefor, means comprising a screw-threaded standard for adjusting the height of said cutting apparatus, mechanism for locking said adjusting means against operation, and means made operative by said locking mechanism and associated with said adjusting means for effecting the feed of said cutting apparatus.

64. In a mining machine, the combination with cutting apparatus, of supporting frame-work therefor, means comprising a screw-threaded standard and a circular nut thereon for adjusting the position of said cutting apparatus, means for locking said nut on said standard to prevent the nut from turning and to hold the cutting apparatus in adjusted position and feed gearing associated with said nut, said feed gearing being made operative by the locking of said nut to effect the feed of said cutting apparatus.

65. In a mining machine, the combination with a plurality of spaced apart parallel kerf cutters, of an intermediate looped chain core cutter having upper and lower runs respectively within the boundaries of said kerf cutters, and means for operating including the feed of said kerf cutters and said looped chain core cutter.

66. In a mining machine, the combination with a main frame, of a supplemental frame pivotally mounted on said main frame, spaced apart plane kerf cutters, an intermediate loop chain core cutter having an unobstructed core opening therethrough, means for supporting said plane kerf cutters and said intermediate loop chain core cutter in position to cooperate with each other in cutting a core of material extending through said unobstructed core opening and through the space between said spaced apart plane kerf cutters, and means for operating said plane kerf cutters and said loop chain core cutter including swing-

ing feeding movement thereof relatively to said supplemental frame.

67. In a mining machine, the combination with a main frame, of a supplemental frame pivotally mounted thereon, a plane kerf cutter mounted on one end of said supplemental frame, a loop chain core cutter having an unobstructed core opening therethrough and mounted on said supplemental frame with the run thereof within the boundary of said plane kerf cutter and in the plane thereof, and, means for simultaneously operating said plane kerf cutter and said loop chain core cutter including the feed thereof.

68. In a mining machine, the combination with supporting framework, of a circular plate adapted to be supported on said framework for rotary movement relatively thereto, a ring rigidly connected to said framework in position to overlap the circular edge of said plate to lock the latter against removal from said framework although permitting free rotation of said plate relatively to said framework, cutting apparatus mounted on said plate to rotate bodily therewith, and means for operating said cutting apparatus including feeding movement thereof while the periphery of said plate moves along the circumferential groove formed at the connection between said ring and said framework.

69. In a mining machine, the combination with a supporting frame of a main frame pivoted thereto, of a supplemental frame pivotally mounted on said main frame, a sleeve connected to said supplemental frame and located at the axis of rotation thereof, cutting apparatus mounted on said supplemental frame, a screw-threaded standard extending into said sleeve and assisting in holding said supplemental frame on its axis of rotation, means associated with said screw-threaded standard for adjusting the height of said cutting apparatus, and means for operating said cutting apparatus.

70. In a mining machine, the combination with a frame having an unobstructed core opening therethrough, of a chain cutter carried by said frame, and separate chain cutters for forming kerfs for spaced apart runs of said first named chain cutter.

71. In a mining machine the combination with a frame having an unobstructed core opening therethrough, of a chain cutter carried by said frame, and a separate chain cutter in position to form a kerf for one of the runs of said first named chain cutter.

72. In a mining machine, the combination with a frame having an unobstructed core opening therethrough, of a chain cutter mounted on said frame, and two additional chain cutters mounted on said frame in position to cut plane kerfs along spaced apart runs of said core cutting mechanism.

73. In a mining machine, the combination with a cutter frame having an unobstructed core opening therethrough, of a supporting frame for pivotally supporting said cutter frame for arcuate movement on an upright axis relatively to said supporting frame, a chain cutter mounted on said cutter frame for travelling around said unobstructed core opening and cutting an upright kerf spaced from said upright axis, separate chain cutters for forming plane kerfs along the inward and outward runs of said chain core cutter, and means for operating all of said chain cutters including arcuate feed thereof by moving said cutter frame arcuately on said upright axis.

74. In a mining machine, the combination with a flat cutter frame provided with a longitudinal recess, of a chain cutter mounted on said frame in position to form a plane kerf, an additional chain cutter having a run extending along said recess in the plane of said flat cutter frame, and means for operating said chain cutters.

75. In a mining machine, the combination with an elongated flat cutter frame having a longitudinal slot, of a chain cutter carried by said elongated cutter frame to cut a kerf in the plane of said frame, an auxiliary cutter frame connected to said first named frame and extending transversely therefrom, and a second chain cutter mounted on said auxiliary frame and having a run extending along said slot in the kerf formed by said first named chain cutter.

76. In a mining machine, the combination with a rigid cutter frame comprising a plane section and a section having an unobstructed core opening therethrough, of a chain cutter mounted on the plane section to cut a plane kerf, and an additional chain cutter mounted on the other section and having a run extending along the plane section within the boundary of said first named chain cutter.

77. In a mining machine, the combination with a cutter frame comprising spaced apart plane sections and an intermediate section having an unobstructed core opening therethrough, of separate chain cutters for the spaced apart plane sections in position to cut spaced apart plane kerfs, and an additional chain cutter mounted on the intermediate section and having spaced apart runs extending along the said plane sections within the boundary of the respective chain cutters on said plane sections.

78. In a mining machine, the combination with a supporting frame, of a supplemental frame mounted for swinging movement on said supporting frame on an upright axis, cutter framework comprising upper and lower spaced apart parallel plane sections and an intermediate section having an unobstructed core opening therethrough, separate

- chain cutters mounted on said spaced apart plane sections in position to cut plane kerfs spaced apart and in parallelism an additional chain cutter mounted on the intermediate section and having outward and inward runs extending along the spaced apart sections within the boundaries of the respective chain cutters thereon, means for actuating the plane kerf cutting chain cutters and said core cutting chain cutter simultaneously and means for swinging said supplemental frame on said upright axis to secure feeding movement of said chain cutters to effect the cutting of a crescent shaped core of material in a general horizontal direction.
79. In a mining machine, the combination with a supporting frame, of a supplemental frame connected by a circular guideway to said supporting frame, cutting mechanism mounted on said supplemental frame, means for operating said cutting mechanism including arcuate movement of said supplemental frame to secure arcuate feeding movement of said cutting mechanism, and means for holding said supplemental frame connected to said circular guideway to prevent said supplemental frame and said cutting mechanism from tipping during the operation thereof.
80. In a mining machine, the combination with a rectangular frame member having an unobstructed core opening therethrough, of a chain cutter guided in a loop about said frame member, supplemental frame members connected to said rectangular frame members, independent chain cutters guided in plane loops on spaced apart portions of said rectangular frame member, and means for operating said chain cutters to effect the cutting of a core of material in a mine wall.
81. In a mining machine, the combination with a cutter head provided with a loop core cutter comprising a frame member having an unobstructed core opening therethrough, of a plurality of endless chain cutters carried by said frame member, and means for operating said chain cutters including feeding movement of said frame member to effect the cutting of a core extending through said unobstructed core opening.
82. In a mining machine, the combination with a cutter head, of a loop chain core cutter comprising a cutter frame having an unobstructed core opening therethrough, and an endless chain cutter carried by said frame, a plane kerf cutter comprising a cutter frame connected to said cutter head, and a chain cutter on said last named cutter frame in position to cut a plane kerf in the plane of one of the runs of said loop chain core cutter, and means for operating said loop chain core cutter and said plane kerf cutter simultaneously, including simultaneous feed thereof to effect the cutting of the core of material extending through said unobstructed core opening.
83. In a mining machine, the combination with a supporting frame, of means for pivotally supporting the rear portion of said supporting frame with the forward portion thereof extending in a general horizontal direction, cutting apparatus mounted on the forward portion of said supporting frame, self-acting power-operated mechanism for adjusting the elevation of said frame to adjust the elevation of said cutting apparatus, and separate additional self-acting power-operated mechanism for adjusting the elevation of the pivotal support at the rear portion of said supporting frame.
84. In a mining machine, the combination with a supporting frame, of means for pivotally supporting the rear portion of said supporting frame, mechanism for adjusting the elevation of said pivotal support, kerf cutting mechanism mounted on the forward portion of said supporting frame for arcuate movement relatively thereto on an upright axis for operation along the roof of a mine chamber approximately in continuation of the plane of such roof while the space above said supporting frame forward of said pivotal support remains free and unobstructed, and means extending downwardly from the lower side of the forward portion of said supporting frame for adjusting the elevation of the forward portion of said supporting frame together with the kerf cutting mechanism mounted thereon.
85. In a mining machine, the combination with a supporting frame, of a pivotal support for the rear portion of said frame, core cutting mechanism having an unobstructed core opening therethrough and mounted on the forward portion of said frame for swinging feeding movement relatively thereto on an upright axis, means applied to the lower forward portion of said frame for adjusting the elevation thereof together with said core cutting mechanism by swinging said frame on said pivotal support while the space above said frame between said core cutting mechanism and said pivotal support remains free and unobstructed, and means applied to said pivotal support at the rear portion of said frame for adjusting the elevation of the rear portion of said frame.
86. In a mining machine, the combination with a supporting frame, of cutting apparatus mounted on the forward portion thereof, a main frame, a pivotal support for the rear portion of said supporting frame, said pivotal support being mounted on said main frame, a standard pivotally connected to the

- forward portion of said main frame and extending into the forward portion of said supporting frame, power mechanism associated with said standard for swinging said 5 supporting frame on its rear pivotal support to adjust the elevation of said cutting apparatus, and power mechanism mounted on said main frame for varying the elevation of said pivotal support to swing the said 10 supporting frame on the pivotal connection between said standard and the forward portion of said main frame.
87. In a mining machine, the combination with kerf cutting mechanism, of a frame for supporting the same, a table mounted on said frame in position for movement into the kerf formed by said kerf cutting mechanism, and means for operating said table by moving the same relatively to said frame 15 and relatively to said cutting mechanism, to remove material dislodged from the mine wall onto said table above the said kerf.
88. In a mining machine, the combination with a supporting frame, of kerf cutting mechanism mounted thereon, a table mounted on said frame in position to enter the kerf cut by said kerf cutting mechanism and means for reciprocating said table in its 20 entirety and back of the kerf-cutting mechanism to transfer dislodged material away from its cut position.
89. In a mining machine, the combination with a supporting frame, of kerf cutting mechanism mounted thereon for arcu- 25 ate feeding movement, an arcuate table mounted on said supporting frame for movement into the kerf cut by said kerf cutting mechanism, and means for reciprocating said arcuate table relatively to said cutting mechanism to effect movement of the dislodged material from its cut position.
90. In a mining and loading machine, the combination with a supporting frame, of kerf cutting mechanism mounted thereon, 30 means for operating said kerf cutting mechanism including feeding thereof, a receiving table without the boundary of said kerf cutting mechanism and mounted on said frame in position to follow said kerf cutting mechanism to move along a kerf cut thereby during the feeding of said kerf cutting mechanism, and means for operating said table independently of said kerf-cutting mechanism to remove dislodged material above the kerf cut by said kerf cutting mechanism and rearwardly of the latter relative to its feeding direction.
91. In a mining machine, the combination with a supporting frame, of kerf cutting mechanism mounted thereon, means for operating said kerf cutting mechanism including the feed thereof, a table mounted on said frame for movement relatively thereto and for movement along the kerf cut by 55 said kerf cutting mechanism and during the feed of said kerf cutting mechanism, and means for imparting short reciprocatory movements to said table, the movements of the table toward the kerf cutting mechanism being comparatively rapid and in the other direction comparatively slow, to effect removal of dislodged material above the kerf cut by said kerf cutting mechanism. 70
92. In a mining machine, the combination with a supporting frame, of kerf cutting mechanism mounted on said frame for arcuate swinging movements on an upright axis, a device movable into the kerf formed by said kerf cutting mechanism for receiving the material severed thereby during continued feeding movement of said kerf cutting mechanism, and means for operating said receiving device during continued feeding movement of said kerf cutting mechanism for transporting material received 75 thereon away from its cut position. 80
93. In a mining machine, the combination with a supporting frame, of a cutter-head carried by said frame for rotation about an upright axis, kerf cutting mechanism carried by said cutter-head, an arcuate table connected to said cutter-head to move therewith and having its forward end always adjacent the rear portion of said kerf cutting mechanism, and means for imparting 85 short reciprocatory movements to said table relative to said cutter-head to effect the transfer of dislodged material from its cut position. 90
94. In a mining machine, the combination with a supporting frame, of kerf cutting mechanism mounted thereon for arcuate movement on an upright axis, an arcuate table mounted on said frame for arcuate movement about said upright axis into the kerf cut by said kerf cutting mechanism and into receiving position immediately back of said kerf cutting mechanism while the latter remains in the plane of said kerf, and means for operating said table back of 100 said kerf cutting mechanism to transport cut material rearwardly from said kerf cutting mechanism and away from its cut position. 105
95. In a mining machine, the combination with a supporting frame, of kerf cutting mechanism comprising a cutter-head mounted on said supporting frame for arcuate movement on an upright axis, an arcuate table flexibly connected to said cutter-head and movable arcuately therewith while occupying a position in the kerf cut by said kerf cutting mechanism and adjacent the rear portion of said kerf cutting mechanism, said arcuate table having upper serrations 110 approximately radial relatively to said upright axis, with the more gradual inclinations of said serrations extending away from said cutting mechanism, and means mounted on said cutter-head for reciprocating said 120 125 130

- arcuate table toward and from the cutting portion of said frame, and a gate pivoted mechanism while maintained in connection to said frame to permit rearward movement with said cutter-head through said flexible connections.
- 5 96. In a mining machine, the combination with a supporting frame, of kerf cutting mechanism mounted on said frame for arcuate movement relatively thereto on an upright axis, an arcuate table mounted on said supporting frame concentrically with said upright axis, said table being movable into the kerf cut by said kerf cutting mechanism and to a receiving position adjacent the rear portion of said kerf cutting mechanism 10 while the latter remains in the plane of said kerf, and means for operating said table independently of movement of said kerf cutting mechanism to transport dislodged material away from its cut position.
- 20 97. In a mining machine, the combination with a supporting frame, of core cutting mechanism mounted thereon, means for operating said core cutting mechanism to cut a crescent-shaped core of material in a mine 25 wall, a receiver connected to said frame and adapted to occupy an arcuate position to receive the arcuate core, means for effecting transfer of the material received by said receiver from its cut position away from the mine wall, and mechanism for permitting free movement of the dislodged material away from the mine wall but automatically preventing the movement of such material back toward the mine wall.
- 30 98. In a mining machine, the combination with a supporting frame, of dislodging mechanism mounted thereon, a chute on said supporting frame, means for transferring dislodged material from the mine wall toward said chute, and a gate pivoted to said frame in position for preventing movement of the dislodged material from said chute back toward the mine wall.
- 35 99. In a mining and loading machine, the combination with a supporting frame, of dislodging mechanism mounted thereon, means mounted on said frame for transferring dislodged material away from the mine wall toward the rear portion of said supporting frame, and a gate mounted on said frame in a predetermined position to have a back and forth movement over substantially the same path of travel relatively to said frame for preventing movement of the transferred material back toward the mine wall during movement of said transferring means back to receiving position.
- 40 100. In a mining machine, the combination with a supporting frame, of cutting apparatus mounted thereon, a receiving table occupying a general horizontal position on said frame, said receiving table being movable relatively to said frame, means for moving said table back and forth to transfer dislodged material toward the rear
- 70 101. In a mining machine, the combination with a supporting frame having a platform, of core cutting mechanism mounted on said frame for arcuate feeding movement on an upright axis, means mounted on said frame for transferring dislodged material away from its cut position over said platform toward the rear portion of said supporting frame, and means for preventing movement of the transferred material back toward the mine wall during movement of said transferring means back to receiving position.
- 75 102. In a mining machine, the combination with a supporting frame, of cutting apparatus mounted thereon, a chute on said supporting frame, means for transferring dislodged material from its cut position toward said chute, and a gate pivoted to said frame for swinging movement relatively to said frame to permit rearward movement of the transferred material but preventing the material from moving back toward the mine wall.
- 80 103. In a mining machine, the combination with a supporting frame, of cutting apparatus mounted thereon in position to cut material at the forward end of a passageway leading to the rear portion of said frame, and a gate pivoted to said frame in position to permit rearward movement of cut material along said passageway but preventing such material from moving back toward the mine wall.
- 85 104. In a mining machine, the combination with a supporting frame, of core cutting mechanism having an unobstructed core opening therethrough and mounted on said frame for arcuate feeding movement on an upright axis, a chute leading to the rear portion of said frame, and a gate pivoted to said frame in position to extend across said chute to permit free movement of cut material from the mine wall to the rear end of said chute but preventing movement of material back toward the mine wall.
- 90 105. The combination with a supporting frame having a lower forward extension comparatively narrow in width, of a mining machine pivotally connected to said supporting frame and extending forwardly over said extension, an auxiliary support connected to the lower side of said mining machine, and a slidable connection between said auxiliary support and said forward narrow extension.
- 95 106. In a mining machine, the combination with a base frame, of a supplemental frame pivotally connected thereto, core cutting mechanism mounted at the forward

portion of said supplemental frame for arcuate feeding movement on an upright axis, a circular base plate for said core cutting mechanism and mounted on said supplemental frame, means connected to said supplemental frame and associated with said circular base plate to permit rotary movement of the latter but prevent tipping thereof as well as tipping of said core cutting mechanism relatively to said supplemental frame, and means for adjustably supporting said supplemental frame at various elevations.

107. In a mining machine, the combination with a base frame, of a supplemental frame pivotally connected thereto, core cutting mechanism mounted on the forward end of said supplemental frame, a supporting screw extending from said base frame through the bottom of said supplemental frame, a nut threaded onto said supporting screw, and means for operating said nut to effect the adjustment of elevation of said core cutting mechanism.

108. In a mining machine, the combination with a base frame, of a supplemental frame pivoted thereto, core cutting mechanism having an unobstructed core opening therethrough and mounted on the forward end of said supplemental frame, a screw threaded post extending from said base frame through the bottom of said supplemental frame, a worm gear nut threaded on said screw threaded post, means for rotating said nut on said post to adjust the elevation of said core cutting mechanism, and means for holding said nut from turning on said post to effect swinging feeding movement of said core cutting mechanism.

109. In a mining machine, the combination with core cutting mechanism having an unobstructed core opening therethrough, of a frame for supporting the same, a screw threaded standard extending through the bottom of said frame but terminating below the upper side thereof, a tube connected to said core cutting mechanism and fitting on said screw threaded standard to guide said frame upwardly and downwardly, a worm gear nut threaded on said standard, means for holding said nut from turning on said standard, and mechanism connected to said worm gear nut for rotating the latter when released to adjust the elevation of said core cutting mechanism and to effect swinging feeding movement of said core cutting mechanism when said nut is held from turning on said standard.

110. In a mining machine, the combination with cutting apparatus, of supporting framework therefor, means comprising a screw threaded member for adjusting the position of said cutting apparatus, mechanism for locking said adjusting means against operation, and means made effective

by said locking mechanism and associated with said adjusting means for effecting the feed of said cutting apparatus.

111. In a mining machine, the combination with cutting apparatus, of supporting framework therefor, means comprising a screw threaded member and a nut thereon for adjusting the position of said cutting apparatus, means for locking said nut on said screw threaded member to prevent the nut from turning and to hold the cutting apparatus in adjusted position, and feed gearing associated with said nut, said feed gearing being made operative by the locking of said nut to effect the feed of said cutting apparatus.

112. In a mining machine, the combination with cutting apparatus, of supporting framework therefor, means comprising a screw threaded member and a nut threaded thereon for adjusting the position of said cutting apparatus, means for locking said nut on said screw threaded member to prevent said nut from turning, and feed gearing meshing with the periphery of said nut and made effective by the locking of said nut to effect feeding of said cutting apparatus.

113. In a mining machine, the combination with a supporting frame, of a supplemental frame, a screw threaded standard, a tube connected to said supplemental frame for fitting on said screw threaded standard for upright sliding movement along said standard, a nut threaded on said standard, means for locking said nut to said supporting frame, power transmission mechanism geared to the periphery of said nut to rotate the latter when unlocked to effect adjustment in elevation of said frames along said standard while being guided by said tube sliding along said standard, cutting mechanism carried by said supplemental frame, and means for driving said cutting mechanism said cutting mechanism being fed by said power transmission means when said nut is locked to said supporting frame.

114. In a mining machine, the combination with a base frame, of a supporting frame pivoted at its rear portion to said base frame, core cutting mechanism having an unobstructed core opening therethrough and comprising a cutter frame mounted on said supporting frame for arcuate movement on an upright axis, a screw threaded standard extending upwardly from said base frame through the bottom of said supporting frame and through said cutter frame at the axis of arcuate movement thereof, a nut threaded on said standard, means for locking said nut to said supporting frame to prevent rotation thereof on said standard, means for driving said core cutting mechanism, and mechanism comprising worm gearing at the periphery of said nut for effecting swing-

ing feeding movement of said core cutting mechanism when said nut is locked to said supporting frame to prevent said nut from turning on said standard.

- 5 115. In a mining machine, the combination with a supporting frame, of core cutting mechanism having an unobstructed core opening therethrough and mounted on said frame for arcuate feeding movement on 10 an upright axis, of a vertical arcuate wall on the forward portion of said frame and having a curvature corresponding approximately to the curvature of the face of the mine wall as left by a previous cut, and 15 means for operating said core cutting mechanism to dislodge a crescent-shaped mass of material while such arcuate wall assists in holding the cut material in its original position at the mine wall.
- 20 116. In a mining machine, the combination with a supporting frame having a forward edge corresponding approximately to the contour of the face of a mine wall as left by a previous cut, of core cutting mechanism having an unobstructed core opening therethrough and mounted on said frame for swinging feeding movement on an upright axis, means for operating said core cutting mechanism including such 25 swinging feeding movement to effect the cutting of a crescent-shaped core of material adjacent the forward edge of said frame, and a vertical arcuate wall extending along a portion of the forward edge of said 30 frame to retain a core of material adjacent such arcuate wall in its original position until loaded.

- 40 117. In a mining machine, the combination with a supporting frame, of core cutting mechanism having an unobstructed core opening therethrough and mounted on said frame for arcuate movement relatively thereto on an upright axis, means for operating said core cutting mechanism to cut a 45 crescent-shaped core of material in an upright mine wall, and an upright arcuate wall on the forward portion of said frame opposite the latter half of the core to assist in holding the latter in its original 50 position until loaded.

- 55 118. In a mining machine, the combination with a supporting frame, of a lateral extension pivoted to the forward portion of said frame at one side thereof, core cutting mechanism mounted on said frame for arcuate feeding movement on an upright axis, means for operating said core cutting mechanism to cut a crescent-shaped core of material, a vertical arcuate wall on the forward portion of said frame, a pivoted extension of said arcuate wall extending along said lateral extension, and a link pivoted at one end to said arcuate wall extension and detachably connected at its other end to said frame to permit the folding of said

arcuate wall extension and of said lateral frame extension during the transportation of the machine.

119. In a mining machine, the combination with a supporting frame, of core cutting mechanism mounted thereon and having an unobstructed core opening therethrough, means for operating said core cutting mechanism including feeding movement thereof on an upright axis to cut a 70 crescent-shaped core of material in an upright mine wall, an arcuate chute having its inner upright wall extended to the forward edge of said frame, a lateral arcuate extension of said inner wall along the forward portion of said frame opposite the latter half of the crescent-shaped core in position to assist in holding such core in its original position until loaded, and means for transferring the core material from the mine 75 wall to said chute for passage along said chute toward the rear end of said frame.

120. In a mining machine, the combination with a supporting frame, of dislodging mechanism mounted thereon, a chute at the 80 rear portion of said frame, means for transferring dislodged material from the mine wall to said chute, and an automatic gate connected to said frame to swing on an upright axis at a position having a fixed relation thereto to confine said gate for back and forth movement over substantially the same path of travel relative to said frame for permitting free movement of the dislodged material toward said chute but preventing movement of the material from said chute back toward the mine wall.

121. In a mining machine, the combination with a supporting frame, of core cutting mechanism having an unobstructed core opening therethrough and mounted on said frame for arcuate feeding movement on an upright axis, an arcuate chute on said supporting frame, means for transferring dislodged material from its cut position toward said chute, and a swinging gate on said frame in position to prevent movement of the dislodged material from said chute back toward the mine wall.

122. In a mining machine, the combination with a supporting frame, of core cutting mechanism mounted thereon for arcuate feeding movement on an upright axis, a chute extending to the rear portion of said frame, means for transferring dislodged material from the mine wall to said chute, and an automatic swinging gate for permitting free movement of the dislodged material toward said chute but preventing movement of the material from said chute back toward the mine wall.

123. In a mining machine, the combination with a supporting frame having a platform, of core cutting mechanism mounted on said frame for arcuate feeding move- 130

ment on an upright axis, means mounted on said frame for transferring dislodged material away from its cut position over said platform toward the rear portion of said supporting frame, a gate pivoted to said frame to swing on an upright axis, and limit stop mechanism connected to said gate for permitting free movement of the transferred material away from the mine wall but preventing movement of the transferred material back toward the mine wall.

124. In a mining machine, the combination with a supporting frame, of a supplemental frame mounted on said supporting frame to swing arcuately on an upright axis, kerf-cutting mechanism mounted on said supplemental frame to swing therewith, a screw-threaded standard located at said upright axis, a nut threaded on said standard, a worm gear on the periphery of said nut, a worm mounted on said supplemental frame and meshing with said worm gear, means for turning said worm to rotate said nut on said standard to adjust the elevation of said kerf cutting mechanism, and means on said supporting frame for engaging said nut to lock the same against turning on said standard to effect swinging feeding movement of said kerf-cutting mechanism upon the rotation of said worm.

125. In a mining machine, the combination with a supporting frame, of a supplemental frame mounted thereon to swing on an upright axis, cutting apparatus mounted on said supplemental frame, a screw-threaded standard associated with said supporting frame, means comprising a worm gear nut on said standard and a worm on said supplemental frame for adjusting the elevation of said supporting frame on said standard to adjust the elevation of said cutting apparatus, and means connected between said supporting frame and said worm gear nut for locking the latter against turning on said standard to effect feeding movement of said cutting apparatus upon the rotation of said worm.

126. In a mining machine, the combination with cutting apparatus, of supporting framework therefor, means comprising a screw-threaded standard and a worm gear nut thereon for adjusting the position of said cutting apparatus, means controllable at will for locking said nut against turning on said standard, and feed gearing made operative by the locking of said nut to effect the feed of said cutting apparatus.

127. In a mining machine, the combination with a base frame, of a mining machine frame pivoted thereto, a screw-threaded standard projecting upward from the forward portion of said base frame in position to support the forward portion of said mining machine frame, mining mechanism carried by said mining machine frame, and

means connected between said mining machine frame and said screw-threaded standard for adjusting the elevation of said mining mechanism, holding the same at adjusted elevation and effecting the feed of said mining mechanism.

128. In a mining machine, the combination with a base frame, of a mining machine frame pivotally connected at its rear portion to the rear portion of said base frame, a screw-threaded standard between the forward portion of said base frame and the forward portion of said mining machine frame, means comprising a worm gear nut on said standard for adjusting the elevation of the forward portion of said mining machine frame, a locking connection between said last-named frame and said nut to prevent the latter from turning, and mining mechanism on said mining machine frame and connected to said worm gear nut to effect feeding when the latter is locked against turning.

129. In a mining machine, the combination of a plurality of chain kerf-cutters, and means for supporting said chain kerf-cutters in position to form a core space bounded at the top, bottom and rear by said chain kerf-cutters and at the front by the face of the mine wall.

130. In a mining machine, the combination with a main frame, of a supplemental frame, core-cutting mechanism having an unobstructed core-opening therethrough and mounted on said supplemental frame for arcuate movement relatively thereto on an approximately vertical axis, means for operating said core-cutting mechanism including arcuate movement thereof to feed the same, and means between said main frame and said supplemental frame for supporting the latter and said core-cutting mechanism at various elevations relative to said main frame while maintaining such axis in such approximate vertical position at the various elevations.

131. In a mining machine, the combination with a loop chain core-cutter, of means for operating the same, including the feed thereof in an arc to dislodge a crescent-shaped mass of material from a mine wall, means for adjusting the height of said core-cutter, a conveyor in position to receive directly by gravity the material dislodged by said core-cutter throughout the arcuate range of movement thereof, and means for operating said conveyor simultaneously with the operation of said core-cutter.

132. In a mining machine, the combination with a core-cutter, of means for operating the same including the swinging thereof on an arc to dislodge a crescent-shaped mass of material from a mine wall, a conveyor, a conveyor frame held in relatively stationary position as to said core-cutter during the op-

eration of the latter, and means for operating said conveyer to take the material from the mine wall toward loading position continuously and immediately after pieces of material break off and fall onto said conveyer frame.

133. In a mining machine, the combination with a supporting frame, of a loop chain core-cutter having an unobstructed 10 core-opening and mounted on said frame for arcuate feeding movement on an upright axis, means for rotating said core-cutter, said rotating means comprising a pair of cooperating gears, one being 15 mounted for rotation on the axis of said core-cutter, and releasable means for holding the concentric gear stationary during the rotation of the other to cause rotation of said core-cutter, said last-named means 20 being releasable to permit rotation of said core-cutter independently of said gears.

134. In a mining and loading machine, the combination with a chain cutter, of means for operating said chain cutter to 25 sever a section of material from a mine vein by forming a kerf in said material, a conveyer mounted on said frame to swing on an upright axis, means for supporting said chain cutter in such position 30 as to cause the same to discharge its cuttings into the path of movement of said conveyer, means for moving the material severed by said chain cutter into position to be transferred by said conveyer toward 35 loading position, and means for controlling the movement of said conveyer at the will of the operator.

135. In a mining and loading machine, the combination with core-cutting mechanism, of means for operating the same, 40 a platform following said cutting mechanism in position to receive the material as it is discharged, a loading conveyer mounted on said frame to swing on an upright axis, and means for effecting the 45 delivery of material from said platform to said conveyer.

136. In a mining and loading machine, the combination with core-cutting mechanism, of a frame for supporting said 50 core-cutting mechanism for operation on an upright mine wall, means for operating said core-cutting mechanism, means for receiving the material as dislodged from the 55 mine vein, a loading traveling conveyor having a receiving hopper at a fixed elevation, a channel for directing dislodged material from said receiving means to said hopper, and means for adjusting the elevation 60 of said core-cutting mechanism and said channel while maintaining delivery communication from the latter to said hopper.

137. In a mining machine, the combination with a supporting frame, of cutting 65 mechanism mounted on said frame for ar-

cuate swinging movement in advance of said frame across the mine wall on an upright axis on said frame, means for operating said cutting mechanism including feeding movement thereof relatively to said frame, means for adjusting the rear portion of said frame from a position adjacent the floor of the mine chamber to a position adjacent the roof thereof, and means for tilting the forward portion of said frame to adjust the inclination of said supporting frame and elevation of said cutting mechanism.

138. In a mining machine, the combination with core-cutting mechanism, of a frame for supporting said core-cutting mechanism for pivotal movement about an upright axis across the mine wall at various elevations, means for adjustably supporting said frame and said core-cutting mechanism at the floor and at the roof and at intermediate positions, and mechanism for adjusting the elevation and inclination of said core-cutting mechanism on said supporting means between the floor 90 and roof of the mine chamber.

139. In a mining machine, the combination with a hopper, of an endless conveyer having superposed portions traveling in opposite directions to and from said hopper to receive material from said hopper and transfer such material toward loading position, a supporting frame having a receiving plate adapted to be located between said hopper and the upright face of the mine 100 wall, kerf-cutting mechanism mounted on said supporting frame, and means separate from said kerf-cutting mechanism for directing cuttings of the latter along said receiving plate into said hopper.

140. In a mining machine, the combination with a supporting frame comprising a platform, of dislodging mechanism mounted on said frame for operation at an upright mine wall above said platform, an 110 adjustable extension on said platform adapted to be moved relatively to said platform to abut against the mine wall to close the gap between the forward end of said platform and said mine wall, and means for yieldingly holding said extension against the mine wall while occupying various positions relative to said platform.

141. In a mining machine, the combination with a supporting frame, of core-cutting mechanism mounted thereon for feeding movement relatively thereto on an upright axis, a carrier mounted on said frame in position to receive the core material as dislodged from the mine vein, means for operating the core-cutting mechanism and independent self-acting power-operated mechanism for moving said carrier relatively to said frame to move the material thereon away from the mine wall.

142. In a mining machine, the combination with a supporting frame having a platform, of core-cutting mechanism mounted on said frame for arcuate feeding movement on an upright axis, means mounted on said frame for transferring dislodged material away from its cut position over said platform toward the rear portion of said supporting frame, and means for preventing movement of the transferred material back toward the mine wall during movement of said transferring means back to receiving position.

143. In a mining and loading machine, the combination with a supporting frame, of dislodging mechanism mounted thereon, a chute at the rear portion of said frame, means for transferring dislodged material from the mine wall to said chute, and an automatic device connected to said frame at a position having a fixed relation thereto to confine said device for back and forth movements over substantially the same path of travel relatively to said frame for permitting free movement of the dislodged material toward said chute but preventing movement of the material from said chute back toward the mine wall.

144. In a mining machine, the combination with a supporting frame, of core-cutting mechanism having an unobstructed core-opening therethrough and mounted on said frame for arcuate feeding movement on an upright axis, an arcuate chute on said supporting frame, means for transferring dislodged material from its cut position toward said chute, and mechanism for preventing movement of the dislodged material from said chute back toward the mine wall.

145. In a mining machine, the combination with a supporting frame, of core-cutting mechanism mounted thereon for arcuate feeding movement on an upright axis, a chute extending to the rear portion of said frame, means for transferring dislodged material from the mine wall to said chute, and an automatic device for permitting free movement of the dislodged material toward said chute but preventing movement of the material from said chute back toward the mine wall.

146. In a mining and loading machine, the combination with a plurality of spaced-apart kerf-cutters, of a core-cutter having an unobstructed core-opening therethrough and extending along the kerfs produced by said spaced-apart kerf-cutters, means for operating said spaced-apart kerf-cutters and said loop core-cutter to cut a core of material in a mine wall, and loading apparatus extending in position to receive dislodged material from said core-cutter.

147. In a mining machine, the combina-

tion with a plurality of spaced-apart plane kerf-cutters, of supporting framework therefor, a core-cutter having an unobstructed core opening therethrough and mounted on said framework in position for cutting a connecting kerf between the kerfs produced by said plane kerf-cutters and spaced back from the mine wall, and means for operating the said plane kerf-cutters and said core-cutter including the feed thereof to effect the cutting of a core of material in its native bed.

148. In a mining machine, the combination with a core-cutter, of a plane kerf-cutter operating in the plane of one of the runs of said core-cutter, and means for adjusting the position of said plane kerf-cutter relatively to said run.

149. In a mining machine, the combination with cutting mechanism, of a support for the dislodged material, a main support for said cutting mechanism and for said first-named support, separate motor means for moving said first-named support in an arc concentric with the feed of said cutting mechanism and following the latter in such arcuate path, and means for guiding said cutting mechanism and said first-named support as a whole in an arc on said main support when the height of the cutting mechanism is adjusted.

150. In a mining machine, the combination with a main frame, of a supplemental frame mounted on said main frame for movement to various elevations, cutting mechanism mounted on said supplemental frame for movement in an arc in a general horizontal direction relatively to said supplemental frame to sever a section from the wall of a mine, a support for the severed section in its entirety following said cutting mechanism and bodily movable therewith to extend under the severed section, and means for moving said last-named support relatively to said cutting means.

151. In a mining machine, the combination with a frame, of core-cutting mechanism mounted thereon, of means for operating said core-cutting mechanism to cut a core in a mine wall in one operation in a general horizontal direction across said mine wall, a platform following and moving with said core-cutting mechanism for receiving material cut from the mine wall by said cutting mechanism as soon as dislodged, and means mounted on said frame for moving said platform relatively to said cutting mechanism and relatively to said frame to cause the same to carry the dislodged material back from the mine wall.

152. A mining machine comprising a supporting frame, cutting mechanism mounted thereon, a segmental platform for receiving the material cut by said cutting mech-

anism, and means for moving said platform independently of said cutting mechanism to the rear portion of said frame spaced from the mine wall, to carry the dislodged material from the mine wall to the rear end of said frame. 65

153. The combination with core cutting mechanism, of a platform following the same and movable therewith to receive the 10 core of material cut from the mine wall by said core cutting mechanism, and means for simultaneously restoring said cutting mechanism to initial position preparatory to another cut and moving said platform to cause 15 the same to carry the core of material intact back from the mine wall.

154. In a mining machine, the combination with a supporting frame, of loop chain core-cutting mechanism mounted on said 20 frame for feeding movement relatively thereto, means for operating said loop chain core-cutting mechanism, a platform conforming to the contour of the unmined mass for receiving material as it is severed from 25 its native position, and means for moving said platform relatively to said supporting frame and relatively to said cutting mechanism to carry said dislodged material away from the mine wall toward loading position.

30 155. In a mining machine, the combination with supporting framework comprising a loading platform at its rear portion, of cutting mechanism mounted on said framework for swinging feeding movement 35 on an upright axis, arcuate receiving mechanism movable under the cut material to receive and carry the same, and means for arcuately and rearwardly moving said arcuate receiving mechanism relatively to said cutting mechanism to deliver the cut material 40 to a position for movement onto said loading platform.

156. The combination with a plurality of 45 kerf cutters, a loop cutter extending through the kerfs produced by said first named kerf cutters, a frame for supporting said first named kerf cutters for operation ahead of said loop cutter, and means for operating said kerf cutters and said loop cutters simultaneously to produce a U-shaped kerf in a mine wall.

157. The combination with a plurality of 55 horizontal kerf cutters, of means for supporting the same parallel to each other and spaced apart, means for operating said kerf cutters to produce substantially parallel kerfs spaced apart in a mine wall, a loop cutter extending through the aforesaid parallel kerfs for producing a connecting kerf 60 between the inner ends thereof, and means for operating said loop cutter.

158. In a mining machine, the combination with a plurality of spaced-apart kerf cutters, of a core cutter for cutting a con-

necting kerf between the kerfs produced by 65 said kerf cutters and spaced back from the mine wall and substantially parallel thereto, and means for operating said kerf cutters and said core cutter including the feed thereof to effect the cutting of a core of 70 material in its native bed.

159. In a mining machine, the combination with a plurality of spaced-apart kerf cutters, of a loop chain core cutter for cutting a kerf between the kerfs produced by 75 said kerf cutters and spaced back from the face of the mine wall and approximately parallel thereto, and means for operating said kerf cutters and said core cutter to cut a core of material in its native bed. 80

160. In a mining machine, the combination with a plurality of spaced-apart kerf cutters, of a loop chain core cutter following said spaced-apart cutters and capable of cutting a kerf spaced back from the mine 85 wall and connecting the kerfs cut by said kerf cutters, and means for operating said kerf cutters and said core cutter to cut a core of material in a mine wall. 90

161. In a mining machine, the combination with a supporting frame, of a plurality of spaced-apart kerf cutters mounted on said frame, a loop chain core cutter having an unobstructed core opening therethrough and mounted on said supporting frame with 95 its upper and lower runs approximately in the respective planes of said spaced-apart kerf cutters and its outer upright run in position to cut a communicating kerf between the kerfs cut by said spaced-apart 100 kerf cutters, and means for operating said spaced-apart kerf cutters and said core cutter, including the feed of all of said cutters, to cooperate in the cutting of a core of material in its native bed. 105

162. In a mining machine, the combination with a supporting frame, of core cutting mechanism comprising a loop chain core cutter having an unobstructed core opening therethrough and also comprising upper 110 and lower kerf cutters spaced apart in accordance with the spacing of the upper and lower runs of said loop chain cutter, means for supporting said core cutting mechanism on said frame in position to cut a core in a 115 mine wall, means for independently adjusting each of said upper and lower kerf cutters relatively to the other and relatively to said frame, and means for operating said core cutting mechanism including feed 120 thereof to cut said core.

163. In a mining machine, the combination with a supporting frame, of a supplemental frame mounted on said supporting frame to swing laterally relatively thereto, a pair of vertically-spaced horizontally-extending traveling endless chain cutters mounted on said supplemental frame, and 125

an upright kerf cutter mounted on said supplemental frame in position to form a kerf substantially in vertical alinement with the outer edges of the kerfs formed by said 5 horizontally-extending kerf cutters.

164. In a mining machine, the combination with a supporting frame, of a pair of vertically-spaced traveling chain kerf-cutters pivotally mounted on said frame for lateral movement relatively thereto, means comprising an upright standard for connecting said kerf-cutters, and an upright kerf-cutter carried by said standard in position to cut a kerf between the kerfs cut by said pair of 10 kerf-cutters.

165. The combination with a self-contained mining machine, of a base frame for supporting said mining machine, pivotal connections on opposite sides of said mining machine, self-acting power-operated means between the forward portion of said mining machine and said base frame for adjusting the inclination of said mining machine up or down on said pivotal connections, and self-acting power-operated means for adjusting the elevation of said pivotal connections to adjust the elevation of the rear 5 end of said mining machine.

166. The combination with a base frame having supporting standards and a lower forward extension, of a mining machine pivotally mounted on said standards to afford an unobstructed space between them for the passage of material to be loaded, and means 10 extending from the bottom of said mining machine to said extension to adjustably support the mining machine at a point spaced from said pivotal connections.

167. The combination with a supporting frame adapted to rest on the floor of a mine 40 chamber, of a supplemental frame mounted on said supporting frame for adjustment in elevation relatively thereto, cutting mechanism carried by said supplemental frame, means for operating said cutting mechanism to sever material from the mine wall at various elevations, a loading conveyer having its receiving end pivotally connected to said supporting frame below the rear 45 end of said supplemental frame, said loading conveyer being mounted on said supporting frame for swinging movement horizontally through angles of over 180° to various angular positions relative to said supplemental frame and without altering the relative position of the receiving end of 50 said loading conveyer and the discharge end of said supplemental frame, and means for transferring severed material from the mine wall at various elevations over said supplemental frame and from the discharge end thereof to the receiving end of said loading conveyer irrespective of the angular 55 position of the latter relative to said supporting and supplemental frames and irre-

spective of the elevation of the cutting operation.

168. In a mining machine, the combination with supporting framework, of a circular plate carried by said framework, a 70 circular guideway for locking said circular plate in a predetermined position on said supporting frame by preventing said plate from tipping relatively to said supporting frame but permitting arcuate movement of 75 said circular plate on an upright axis, core-cutting mechanism mounted on said circular plate for feeding movement therewith, and means for operating said core-cutting mechanism including feeding movement thereof 80 by moving said circular plate arcuately relatively to said supporting frame while being locked as aforesaid.

169. In a mining machine, the combination with supporting framework, of a circular guideway thereon, a circular plate 85 rotatably mounted in said guideway, a ring secured to said supporting frame and overlapping said guideway and the peripheral portion of said circular plate to 90 form an annular groove for the peripheral edge of said plate and to confine said plate in said circular guideway to prevent said plate from tipping relatively to said supporting framework, core-cutting mechanism 95 mounted on said circular plate for bodily movement therewith on an upright axis, and means for operating said core-cutting mechanism including arcuate feed thereof by rotating said plate in said circular guideway relatively to said supporting framework on an upright axis while being confined in 100 said annular groove and prevented from tipping relatively to said supporting frame by said ring.

170. The combination with a self-contained mining machine comprising core-cutting mechanism adapted to operate on an upright axis, of supporting framework comprising a base and a screw-threaded standard 110 thereon, and mechanism connected between said mining machine and said standard for adjusting the elevation of the core-cutting mechanism and holding the same at adjusted elevation.

171. The combination with a base supporting frame, of a self-contained mining machine, pivotal connections between said frame and the rear portion of said mining machine, means between the forward portion of the mining machine and said frame to afford said mining machine additional support, and self-acting power-operated mechanism for adjusting the elevation of 115 said mining machine and said additional support while tilting it on said pivotal connections.

172. The combination with a supporting frame comprising spaced apart upright supporting standards and a forwardly project- 120 125 130

ing base, of a mining machine pivotally mounted on said standards, and an auxiliary upright standard pivotally mounted on the forwardly projecting base and connected 5 to the forward under portion of said mining machine to secure a third point of support for said mining machine.

173. The combination with a supporting frame having spaced-apart upright standards and a forwardly projecting portion, of a mining machine adapted to be mounted on said frame for adjustment in elevation relatively thereto, spaced-apart pivotal supports on said standards and connected to the 10 rear portion of the mining machine to enable the latter to swing up or down on the said pivots on a horizontal axis, and means at a third point of support between said mining machine and said projecting portion 15 to adjust the elevation of the forward portion of the mining machine by swinging the same on said pivots.

174. In a mining machine, the combination with a supporting frame, of a cutter frame mounted on said supporting frame and having an unobstructed core-opening therethrough, cutting mechanism mounted on said cutter frame, means for operating said cutting mechanism, and means adapted 30 to act separately in spaced-apart positions for rectilinearly adjusting the elevation of said cutter frame relatively to said supporting frame while maintaining operating connections for said cutting mechanism.

175. In a mining and loading machine, the combination with kerf-cutting mechanism mounted for feeding movement in an arc about an upright axis, means for operating said kerf-cutting mechanism including 40 arcuate feeding movement about said upright axis, a device also movable in an arc about such upright axis for receiving the material and carrying the same toward loading position, means independent of said operating means for operating said receiving device.

176. In a mining machine, the combination with a main supporting frame, of a supplemental frame, core-cutting mechanism having an unobstructed core-opening therethrough mounted on said supplemental frame for arcuate feeding movement relatively thereto on a vertical axis and for adjustment with said supplemental frame as a 50 whole in elevation relatively to said main supporting frame, connections between said supporting frame and said supplemental frame for maintaining said axis in vertical position for various elevations of said core-cutting mechanism, and means for operating said core-cutting mechanism including arcuate feeding movement thereof on such vertical axis at the various elevations of said core-cutting mechanism.

177. In a mining machine, the combina-

tion with a main frame, of a core-cutter, means for supporting said core-cutter on said main frame for adjustment in elevation relatively thereto, apparatus applied to the forward portion of said frame and also 70 to the rear portion thereof for lifting and lowering said supporting means in straight up and down movements relatively to said main frame to adjust the height of said core-cutter in its entirety, and means for 75 operating said core-cutter including feed thereof in the various positions to which adjusted in elevation.

178. In a mining machine, the combination with a core-cutter having an unobstructed core-opening therethrough, of a supporting frame therefor, means comprising spaced-apart actuating devices for adjusting the height of said core-cutter by moving all parts thereof relatively to said supporting frame up or down along vertical lines, and mechanism for operating said core-cutter including the feed thereof in its various positions to which it has been thus 85 adjusted.

179. In a mining machine, the combination with mechanism for entirely cutting out a section of material from the wall of a mine, of means extending under the core in position to receive the severed section of 95 material directly from its original position in the mine wall, and apparatus independent of said cutting means for moving said receiving means horizontally to carry the material thereon horizontally back from the 100 mine wall toward loading position.

180. In a mining machine, the combination with supporting framework, of core-cutting mechanism having an unobstructed core-opening therethrough and mounted on 105 said framework to swing on an upright axis, means mounted on said framework and movable relatively thereto in position to move under the cut core and receive the same, said receiving means being capable 110 of carrying the dislodged material away from the mine wall toward loading position when said receiving means is moved relatively to said framework, means for operating said core-cutting mechanism including 115 arcuate feeding movement thereof by swinging the same on said upright axis relatively to said framework, and independent means for operating said receiving means.

181. In a mining machine, the combination with cutting mechanism, of means for operating said cutting mechanism to entirely cut out from the wall a section of material, a rigid device for said cutting mechanism to extend under a section of material as it is being cut in position for receiving the cut material from above, and means independent of the first-named operating means for operating said receiving 125 means to cause the same to carry into load- 130

ing position the section of material resting said cutting mechanism to receive the core by gravity thereon.

182. A mining and loading machine comprising a supporting frame, core-cutting mechanism mounted thereon, means for operating said core-cutting mechanism including arcuate feeding movement thereof relatively to said supporting frame, and means separate and independent of said 5 operating means and mounted on said frame 10 in position to extend under the core cut by

In testimony whereof I have signed my name to this specification, in the presence of 15 two subscribing witnesses, on this 14th day of March, A. D. 1916.

EDMUND C. MORGAN.
